US00D943239S

(12) United States Design Patent (10) Patent No.: US D943,239 S
(45) Date of Patent: * Feb. 15, 2022

(54) BRA TAPE

(71) Applicant: Quji Zhao, Guangzhou (CN)

(72) Inventor: Quji Zhao, Guangzhou (CN)

() Term: 15 Years

(21) Appl. No.: 29/729,017

(22) Filed: Mar. 24, 2020

(51) LOC (13) Cl. 02-01

(52) U.S. Cl.

USPC D2/706

(58) Field of Classification Search

USPC D2/702, 703, 706-710, 718-727, 731,
D2/737, 739

CLAIM

The ornamental design for a bra tape, as shown and described.

DESCRIPTION

FIG. 1 is a front perspective view of a bra tape showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash lines in the figures represent the shading lines of the bra tape that form no part of the claimed design.

1 Claim, 8 Drawing Sheets
